UNITED STATES PATENT OFFICE.

WILLIAM HADDOCK, OF NEWTON, MASSACHUSETTS.

PLANER-GAGE AND CALIPERS.

SPECIFICATION forming part of Letters Patent No. 380,797, dated April 10, 1888.

Application filed December 30, 1887. Serial No. 259,407. (No model.)

To all whom it may concern:

Be it known that I, WILLIAM HADDOCK, a citizen of the United States, residing at Newton, in the county of Norfolk and State of Massachusetts, have invented certain new and useful Improvements in Planer-Gages and Calipers, of which the following is a specification.

My invention relates to improvements in planer-gages and calipers; and the objects of my invention are to provide a convenient tool for use in connection with planing-machines for setting the planer-tools, for an inside and outside calipers, for a depth-gage, scratch-gage, and surface-gage, and in general to improve the efficiency of the device.

In the accompanying drawings, Figure 1 is a side elevation of my planer-gage and calipers. Fig. 2 is a plan view of the same. Fig. 3 is a front elevation, partly in vertical section. Fig. 4 is a detached side elevation of the setting-arm with a depth-gage attached, the latter being shown partly in vertical section. Fig. 5 is a front elevation of said depth-gage; 25 and Fig. 6 is an enlarged vertical section, partly in elevation, of a portion of my planer-gage, showing the manner of securing and adjusting the measuring-screw in the frame.

A designates the base or bed of the frame B. 30 C designates the measuring-screw, fitted against longitudinal movement within the upper end of the frame B and provided with an operating button or cap, D. Upon the upper part of the frame A is an index-mark, a, Fig. 35 1, and on the periphery of the button D, near its base, are vertical marks which divide said periphery into twenty-five divisions. The screw C is threaded with forty threads to the inch, so that a movement of one division of 40 the screw registers one-thousandth of an inch, all substantially as in an ordinary micrometer-calipers.

In order to compensate for wear, the split nut E upon the body of the screw is adjusted laterally by a clamp-screw in the ordinary manner, and in order to adjust the screw C with reference to its length, so that it shall properly register with the under face of the base A, which represents the zero-line, I provide the screw-threaded bushing g in the upper part of the frame, as shown in Fig. 6, which

bushing may be turned by a proper screw-driver inserted in the slot at its upper end, and when adjusted may be held in place by the set-screw s, the operating-button being removed when it is desired to adjust the measuring-screw. 55

Extending rearwardly from the split nut E is a measuring-arm, b, having upon its side the index-mark c. Extending in the opposite direction from the nut E is a lug or bracket, d. To the end of this bracket I pivot the setting-pointer F, having at its outer end the setting-arm e. A spring, f, has one end rigidly attached to the setting-pointer F, while its other end rests in a slot in the measuring-arm b, whereby the setting-pointer F is held in position to register with the index-mark c whenever said arm is not forced out of position. 70

An upright at the front end of the frame B has fixed upon it a scale, g, graduated to represent twenty-five thousandths of an inch, the figures on said scale designating the longer marks of said graduations, the same being 75 every fourth graduation-mark, and consequently representing tenths of an inch. As shown in the drawings, the scale g is to be read from the upper edge of the measuring-arm. Within a slot at one edge of the base there is 80 a swinging caliper-arm, G, pivoted to said base, which when not wanted for use is turned into the position shown in the drawings, and when wanted for use as a caliper-arm it is swung around to the front immediately 85 opposite the setting-arm e, as indicated by broken lines in Fig. 1.

In Figs. 4 and 5 I have shown a depth-gage adapted for use upon the end of the setting-arm e. This depth-gage consists of a socket-piece, h, adapted to fit the end of the setting-arm e, as shown in Fig. 4, and a screw-pin, k, provided with a threaded neck, by which it is attached and detached to and from the lower end of the socket-piece. I have illustrated 95 only one of these screw-pins; but, if desired, a number of them of different lengths may be provided. I have illustrated a set-screw, m, for fastening the socket-piece h upon the setting-arm e; but in practice I intend to fit the 100 socket-piece to the setting-arm so accurately that it will stay in place by friction, and

thereby dispense with the use of the set-screw *m*.

Upon that side of the split nut *E* which is opposite the measuring-arm *b* there is a projecting screw, *n*, upon which is mounted the split clamp *H*, for holding the scratch *o*, and upon the outer end of said screw is the thumb-nut *J*, for holding the clamp *H* in position and binding it upon the body of the scratch.

10 Supposing it were required to set the planer-tool one-half inch above a given surface, the measuring-screw would be turned to bring the top of the measuring-arm *b* to the graduation represented by the figure 5 on the scale, and 15 with the zero-mark on the operating-button *D* to register with the index *a*, in which case the upper surface of the setting-arm *e* would be just half an inch above the lower face of the base *A*. The base is then set upon the surface to be gaged from, and the planer-tool is brought down upon the top face of the setting-arm *e* so as to contact therewith, but still leave the pointer *F* directly upon the index *c*. It will readily be seen that if the tool is 20 brought down too far the pointer will be carried off from its index.

The depth-gage may be used for measuring a slot or hole, the pointer indicating whether or not the end of the screw-pin of the depth-gage is in contact with the bottom of the slot or hole, so that its depth may be measured or the slot or hole sunk until it is of the required depth.

With the caliper-arm *G* swung around so as 35 to form a companion arm for the setting-arm *e*, the device can be used for an inside or outside calipers. When used as an inside calipers, the measure registered or desired may be read from the top of the measuring-arm *b*, and by 40 making the vertical width of the measuring-arm *b* at the point where it covers the scale *g* equal to the sum of the widths vertically of the arms *e* and *G* the measure for an outside calipers may be correctly read from the under 45 edge of the measuring-arm *b*. As illustrated in the drawings, the nut *E* would come in contact with the top of the base *A* as soon as the bottom of the measuring-arm *b* is in the same plane as the under face of the base *A*, and as 50 said arm *e* is about one-eighth of an inch in height the tool as arranged must read from one-eighth of an inch upward. If desired to have the upper face of the setting-arm *e* operate from the zero-line upward, it is only neces-

sary to shorten the under side of the nut *E* or 55 correspondingly lower the scale *g* and setting-arm *e*.

The operation of the scratch-gage will be readily understood. By loosening and tightening the nut *J* the scratch may be adjusted 60 to any desired position, when it may be used for marking or measuring work, and by raising and lowering it with the measuring-screw it may be used for laying out marks any desired distance apart. 65

I claim as my invention—

1. The frame *B*, having base *A*, in combination with the measuring-screw *C*, the nut *E*, and the setting-arm *e* and pointer *F*, mounted on said nut, substantially as described, and for 70 the purpose specified.

2. The combination of the frame *B*, having base *A* and scale *g*, the measuring-screw *C*, the nut *E*, measuring-arm *b*, registering with the scale and having the index *c*, and the pointer *F*, 75 pivotally mounted on a bracket which extends from the nut *E* and provided with the setting-arm *e*, substantially as described, and for the purpose specified.

3. The combination of the measuring-screw 80 and nut with the caliper-arm *G*, setting-arm *e*, the pointer *F*, pivotally mounted, and the index-mark *e* on an arm extending from the nut *E*, substantially as described, and for the purpose specified.

4. The combination of the measuring-screw and nut having an arm carrying the index 85 *c*, the pointer *F*, pivoted upon an extension of the nut and bearing the setting-arm *e*, and the depth-gage fitted to the arm *e*, substantially 90 as described, and for the purpose specified.

5. The combination of the frame *B*, having base *A*, the under face of which represents the zero-line, the measuring-screw *C*, nut *E*, and bushing *q*, for regulating the endwise adjustment of the screw *C*, substantially as described, and for the purpose specified. 95

6. The combination of the measuring screw, the nut *E*, having the arm with index-mark *c*, the pointer pivoted upon an extension of said 100 nut and having the setting-arm *e*, and a spring for holding the pointer to the index-mark, substantially as described, and for the purpose specified.

WILLIAM HADDOCK.
